UNITED STATES PATENT OFFICE.

WENCESLAS V. JEAN, OF MINNEAPOLIS, MINNESOTA.

ORE-SEPARATING MACHINE.

No. 926,493.

Specification of Letters Patent. Patented June 29, 1909.

Application filed April 20, 1908. Serial No. 428,014.

To all whom it may concern:

Be it known that I, WENCESLAS V. JEAN, of Minneapolis, Hennepin county, Minnesota, have invented certain new and useful 5 Improvements in Ore-Separating Machines, of which the following is a specification.

My invention relates to machinery designed to effect a separation of iron and other metals capable of magnetic influence from a 10 body of other material, and the object of the invention is to provide an apparatus of large capacity and one in which the separation of ore can be thoroughly and rapidly performed.

The invention consists generally in various 15 constructions and combinations, all as hereinafter described and particularly pointed out in the claims.

In the accompanying drawings, forming 20 part of this specification, Figure 1 is a vertical sectional view of an ore separating machine embodying my invention. Fig. 2 is a detail sectional view of the same. Fig. 3 is a detail view illustrating the construction of one of the circuit closing rings.

25 In the drawing, 2 represents a tank adapted to contain the material to be treated, a sufficient amount of water being introduced into the tank to render the material of proper consistency for separation.

30 3 is a valve controlling the water supply and 4 is an upright hollow shaft supported on a step 5 within the tank and carrying an agitating device consisting of a series of radial tubes 6 having perforations 7 through 35 which air under pressure is delivered to the tank from a pipe 8 connected with said hollow shaft. The air entering the mixture through the revolving arms of the agitating device has the effect of stirring it up and preventing the ore from settling to the bottom 40 of the tank. The shaft 4 is driven through a gear 9 thereon meshing with a pinion 10 on a shaft 11 having a driving pulley 12.

A wheel 13 is mounted on a shaft 14 and 45 supported in a vertical plane with a portion depending within the solution in the tank. This wheel is arranged to revolve slowly and is divided into a series of sections 15. I have shown 8 of these sections but a greater 50 or less number may be employed, if preferred. In each section I arrange a series of electro-magnets 16 having their pole pieces projecting beyond the periphery of the wheel, as indicated in Fig. 1.

55 Upon the shaft 14 I arrange a series of rings 17 insulated from one another and from

said shaft, the number of rings corresponding to the number of sections in the wheel and each ring being in circuit with one side of the electro-magnets of one of the sections, 60 and all of the rings being in circuit with a dynamo (not shown), through brushes 18 and a conductor 19. A ring 20 is provided having a brush 21 in circuit with the dynamo through a conductor 22, and the said ring 20 65 is in circuit with the other side of the electro-magnets of all of the sections. The rings 17 are provided with contacting surfaces 23 and insulating or non-conducting surfaces 24, the brushes 18 sliding over said surfaces as 70 the rings revolve with the shaft 14. With this arrangement it is evident that during a predetermined period in the revolution of the wheel 13 the circuit will be closed through the electro-magnets of each section and their 75 pole pieces energized, and during another period in the revolution of the wheel the circuit will be broken through the electro-magnets and their pole pieces deenergized. The rings 17 are so arranged that the magnets 80 will be energized when they are passing through the solution in the tank and will be deenergized when they reach a point where the material collected on the pole pieces through magnetic attraction will, when relieved, fall upon the inclined plate 25 and be conducted to a suitable receptacle. A brush 85 26 is arranged above said plate and adapted to contact with the pole pieces and sweep off any particles of iron or other metal adhering 90 thereto. The groups of magnets are arranged in water-tight compartments in the sections 15 of the ring, their pole pieces only being exposed to attract the ore and separate it 95 from the solution in the tank.

In the operation of the machine the tank is filled with water to a point near the top and a quantity of finely ground ore introduced. The agitator is set in motion and air under pressure being discharged through the holes 100 7 will cause a violent agitation of the water and the particles of ore to be held in suspension. The wheel 15 is now set in motion and an electric current turned on. As each group of electro-magnets passes through the 105 solution a quantity of iron will adhere to the magnets and be carried out of the tank. Upon reaching a predetermined point the circuit will be broken through the magnets, their pole pieces demagnetized and the 110 greater portion of the iron will fall upon the inclined plate 25. The revolving brush

keeps the pole pieces clean, and upon reaching a point where the magnets can enter the solution the circuit will be closed therethrough, the ore will collect on the pole pieces and the process may be repeated as long as any iron remains in the solution.

I claim as my invention:

1. The combination, with a tank adapted to contain a liquid solution and a quantity 10 of finely ground ore, of a magnetic separating element mounted on said tank, a hollow shaft depending within said tank, a series of tubes radiating from said shaft near the bottom of said tank, there being an unob- 15 structed space between said tubes and said magnetic separating element, said tubes having perforations in their walls, and a pipe arranged to introduce air under pressure into said shaft.
2. The combination, with a tank adapted 20 to contain a liquid solution and a quantity of finely ground ore, of a magnetic separating element mounted on said tank, an agitat-

ing device provided within said tank and comprising a hollow shaft, a series of tubes 25 radiating therefrom and having perforations in their walls and means for supplying a fluid pressure to said shaft and tubes.

3. The combination, with a tank, adapted to contain a liquid solution and a quantity 30 of finely ground ore, of a magnetic separating element, there being unobstructed space beneath said separating element within said tank, and an agitating device consisting of a hollow shaft and arms radiating therefrom 35 provided near the bottom of said tank and arranged to revolve therein, said agitating device having means for delivering a fluid pressure into the lower portion of said tank, for the purpose specified.

In witness whereof, I have hereunto set my hand this 15th day of April, 1908.

WENCESLAS V. JEAN.
